UNITED STATES PATENT OFFICE.

CHARLES R. MILLER, OF LANSINGBURG, NEW YORK.

HOLDBACK ATTACHMENT FOR HARNESS.

SPECIFICATION forming part of Letters Patent No. 334,883, dated January 26, 1886.

Application filed June 25, 1885. Serial No. 169,723. (No model.)

To all whom it may concern:

Be it known that I, CHARLES R. MILLER, of the village of Lansingburg, county of Rensselaer, State of New York, have invented a new and useful Improvement in Holdback Attachments to Animal-Harness, of which the following is a specification.

My invention relates to that class of devices which form a part of animal-harness, and such as are used to connect the hames with a holdback-plate on which the end rings of the neck-yoke slide as the poll vibrates.

My invention consists (as will be more fully detailed hereinafter in connection with its illustration) in the combination, with a curved holdback slide-plate that is made in two parts, of a snap arranged to connect with the hame at each side of the neck, the shanks of said snaps being made long enough to form direct connection with the holdback-plate by means of a hinge formed on the snap-shank and said holdback-plate, with the finger-piece that operates the snap-latch located on the inner side of the snap proper instead of on the outer side or top.

The object of my invention is to make the connection between the holdback-plate and snap-shank adjustable relatively to each other only on the line of their hinged attachment, as distinguished from a pivotal connection produced by an eye on the snap-shank, which would allow the holdback-plate to swing around on the snap end, or the latter to swing around on the holdback-plate.

Another object of my invention is to arrange the finger-piece of the snap-bolt on the inside of the latter, as distinguished from placing it on the top or outer side of the snap-barrel, where the hame-rings or lines can catch onto the finger-piece and disconnect the snap.

Accompanying this specification, to form a part of it, there is a sheet of drawings containing two figures illustrating my invention, with the same designation of its parts by letter-reference used in both of them.

Of these illustrations, Figure 1 is a perspective of my improved holdback attachment with one of the snaps and shanks removed. Fig. 2 is a longitudinal central section of the snap and part of the snap-shank shown at Fig. 1.

The several parts of the apparatus thus

illustrated are designated by letter-reference, and the function of the parts is described as follows:

55

The letter H designates the curved holdback-plate, which is constructed with a recess, R, in its upper surface, this recess being made to receive a wearing-piece, W, the latter being constructed to be secured in said recess by means of a bolt, B.

The letters E E indicate hinging-ears, of which there are two at each end of the curved holdback-plate H, and they are adapted to receive hinging-journals j at the lower end of the snap-shank K, so that the snap-shank and holdback-plate are free to move on such hinged connection.

The letter I designates a strap-passage for the bell-strap, which opening is made in the holdback-plate near one of its ends.

The letter S designates the snap, which has a latch-bolt, D, that is actuated by a spiral spring, e, that operates to force the outer end of the bolt to close against the end h of the hook G, the spring encircling that part of the bolt that is within the cylindrical interior of the snap-body in the usual manner. This latch-bolt D has a finger-piece, p, that is projected from the side of the bolt through a slot, 80 m, made in the side of the snap-body to connect with its interior.

The letter v indicates the usual vent-opening.

As thus arranged, the holdback attachment has a hinged connection between it and the snap-shank, and an adjustment thereof which is limited to the line of the hinge action, and this makes the connection more steady. The holdback-plate being made with a recess to receive a new wearing-piece when cut away by the yoke-chains thereat makes the attachment last longer, and the snap, by having its finger-piece at the side instead of the top, is less likely to be disconnected by the hame-rings or the lines.

The holdback is preferably made with the recess to receive an inserted wearing-piece; but the holdback may be made solid thereat, provided the other features of the combined parts are used as I illustrate and describe them.

While I prefer to use a snap made as shown—with the finger-piece arranged on the

side of the snap-body—yet any kind of snap 5 may be employed that will connect directly with the hame-rings, and which has a long shank that is hinged to the holdback-plate, as I illustrate and describe it; and while I prefer to make the hinging-eyes on the forked ends 10 of the holdback-plate, and the hinging-journals on the elongated snap-shank, yet, if desired, the forked ends for the hinging-eyes may be made upon the snap-shank, and the hinging-journals on the holdback-plate. In either instance the improved function of the parts will be the same.

Having thus described my invention, what I 15 claim, and desire to secure by Letters Patent, is—

1. The combination, with the holdback-plate H, made with hinging-eyes E E at each of its ends, of the snap-shanks K K, made with the 20 journals j j at each of their lower ends, and having the snaps S rigidly secured to their upper ends, said parts being constructed and arranged to operate substantially as set forth.

2. The combination of the curved holdback-plate H, made with the centrally-located recess R, wearing-piece W, and with hinging-eyes E E at each end, and the snap-shanks K, made with the journals j at their inner ends and the snaps S at their upper ends, said parts being constructed and arranged to operate substantially as set forth. 25 30

3. The combination of the snaps S S, made with their finger-pieces at the side, the snap-shanks K, made with hinging-journals j, and the holdback-plate H, made with the hinging-eyes E at each end, all constructed to operate substantially in the manner as and for the purposes set forth. 35

Signed at Troy, New York, this 2d day of May, 1885, in the presence of the two witnesses whose names are hereto written.

CHARLES R. MILLER.
